UNITED STATES PATENT OFFICE

ALEXANDER FREDERICK JENKINS, OF BALTIMORE, MARYLAND

PAINT-SPRAYING APPARATUS

Application filed January 2, 1929. Serial No. 329,774.

The present invention relates to paint spraying devices and more particularly to devices of this type by means of which paint or the like may be sprayed by means of compressed air, such for instance as is disclosed in my co-pending application Serial No. 159,849, filed January 8, 1927. The object of the present invention is to provide an improved mechanism whereby the paint spray valve employed with devices of this nature may be operated with greater facility and freedom from error. The invention may have various forms and in the accompanying drawings one embodiment thereof is illustrated by way of example. It will be appreciated, however, that minor changes may be made in the design and arrangement of the component elements of the invention without departing from its spirit and scope.

20 In the drawings:-

Figure 1 is a side elevation of a paint spray device embodying the improvements constituting the present invention;

25 Figure 2 is a section on line 2—2 of Figure 1; and

Figure 3 is a perspective view of one of the details.

Since the details of the interior passages and operating parts of the spray gun form no part of the present invention, they are not illustrated, and it will be sufficient for present purposes to explain that the paint spray device illustrated comprises essentially a body portion 10, a handle or grip portion 11 and a nozzle portion 12 mounted on the forward end of the body portion. Air flows to the discharge nozzle from a source of supply of compressed air which is connected to a coupling 13 which will be seen at the 30 foot of the grip or handle 11, and makes its way to the nozzle through passages which are not illustrated, the flow of air being controlled by a valve positioned in a valve casting 14, which valve may be operated from 35 without by longitudinally reciprocating the valve stem 15. The paint or other liquid to be discharged from the nozzle is drawn or forced upwardly through a conduit within the coupling member 16 and the flow of this 40 liquid to the discharge nozzle is controlled

by a valve, not shown, which valve is of the needle type and is operable by the longitudinally reciprocable valve stem 17. Movement of valve stems 15 and 17 toward the right (Figure 1) results in opening of both 55 the air and liquid valves and movement toward the left in the closing thereof.

A trigger or operating lever is indicated at 18, this trigger being preferably stamped of sheet metal and bifurcated at its upper 60 end to receive the body 10, the extreme upper ends of the arms of the lever being pivoted at 19 to an upward extension of the body. A yoke shaped member 20, more clearly illustrated in Figure 3, is pivoted at 21 65 to the arms of operating lever 18, this last mentioned member having forwardly extending side portions and a transverse portion 20' formed with a notch 20² to receive the liquid valve stem 17. Member 20 has 70 also a rearwardly extending portion 20³ comprising a finger piece and by means of which it may be rocked from the full line position, Figure 1, to the dotted line position. Immediately in rear of the transverse portion 20' of member 20 is an abutment member 22, either fixed on stem 17, or adjustably 75 secured on said stem.

It will be apparent that movement of the lower end of operating lever 18 toward the 80 right (Figure 1) when member 20 is in its full line position, will result in simultaneous movement of stems 15 and 17 toward the right and in simultaneous opening of the air and paint valves.

At times it is desirable to operate the air valve alone to effect the discharge of air from the nozzle, without simultaneously discharging paint. This result may be brought about by locking the yoke 20 to its dotted line position, in which position it wholly disengages the stem 17 and abutment 22 so that its movement to the right results in no movement of the paint valve operating stem 17.

In the normal operation of the paint spray device however it is necessary that the yoke member 20 remain in its full line position so that both valve stems 15 and 17 will be operated upon a movement of lever 18. For that reason I have provided member 20 with 85 90 95 100

a portion 20⁴ which constitutes a latch, cooperating with stem 17 in locking this member in the position in which it is shown in Figure 1. As can be seen from Figure 2 the latch 5 20⁴ will prevent accidental raising of the yoke 20 since it projects somewhat beneath stem 17. To effect disengagement of members 17 and 20 it is necessary to exert a considerable pressure on the finger piece 20³ to bring the 10 latch 20⁴ above this stem, the lever 18 and member 20 being constructed of sheet metal or other resilient material possessing sufficient springiness to permit the slight necessary lateral movement of latch 20⁴ in moving 15 from one side of the stem 17 to the other. The yoke 20 is therefore normally locked in its lowermost position, effecting an operative connection between lever 18 and stem 17, except when the operator definitely desires a 20 disconnection and effects the same by a substantial pressure upon the finger piece 20³. Accidental disengagement, such as has been experienced by those operating devices of this 25 nature, is wholly avoided.

Having thus described the invention, what is claimed as new and desired to be secured by Letters Patent is:—

1. A paint spraying apparatus comprising a body, a discharge nozzle mounted thereon, a handle, air and paint valve operating stems, a lever for operating both of said stems and a separable connection between said lever and the paint valve operating stem which connection includes a member pivotally secured 25 to the operating lever a portion of which constitutes a latch adapted to cooperate with the paint valve stem, the lever and member being of resilient material whereby said portion is permitted to spring laterally in passing the said stem and to spring to original 30 position thereafter.

2. A paint spraying apparatus comprising a body, a discharge nozzle mounted thereon, a handle, air and paint valve operating stems, a lever for operating both of said stems and a separable connection between said lever and the paint valve operating stem which connection includes a yoke shaped member having 45 its parallel sides pivotally secured to said lever and a portion extending transversely of the paint valve stem, said last mentioned portion having a notch to receive said stem, one edge of said notch having a projecting portion constituting a latch adapted to cooperate 50 with said stem in holding said yoke in its stem engaging position, the lever and yoke being of resilient material whereby said portion is permitted to spring laterally in passing 55 said stem and to spring to original position thereafter.

In testimony whereof I hereunto affix my signature.

ALEXANDER F. JENKINS.
